United States Patent Office

Des. 184,837
Patented Apr. 7, 1959

184,837

COMBINED TABLE AND SEAT UNIT

Glen T. Sutfin, Metropolis, Ill.

Application February 4, 1957, Serial No. 44,724

Term of patent 14 years

(Cl. D33—14)

FIG. 1

FIG. 2

FIG. 3

Fig. 1 is a perspective view of a combined table and seat unit showing my new design.

Fig. 2 is a side elevational view thereof.

Fig. 3 is an end elevational view thereof.

The dominant features of the design reside in the portions shown in full lines on the drawing.

I claim:

The ornamental design for a combined table and seat unit, as shown and described.
